UNITED STATES PATENT OFFICE.

ALEXANDER F. KUHNEN, OF DIXON, ILLINOIS, ASSIGNOR TO AMERICAN WAGON COMPANY, OF CHICAGO, ILLINOIS, A CORPORATION OF ILLINOIS.

WAGON-BODY.

1,353,351.

Specification of Letters Patent. Patented Sept. 21, 1920.

Application filed November 11, 1918. Serial No. 261,986.

To all whom it may concern:

Be it known that I, ALEXANDER F. KUHNEN, a citizen of the United States, residing at Dixon, in the county of Lee and State of Illinois, have invented certain new and useful Improvements in Wagon-Bodies, of which the following is a specification.

This invention relates to improvements in wagon bodies of the general type of construction shown, for example, in Letters Patents of the United States, Nos. 917,960, granted April 13, 1909, on the application of William A. Melrose and James M. Overshiner, and 1,066,937, granted July 8, 1913, also on the application of William A. Melrose and James M. Overshiner. These patents illustrate and describe a type of wagon body construction which is so arranged that a variety of shapes of body for diverse uses may be provided simply by moving or readjusting various portions of the body into different positions. More particularly it may be mentioned that the type of body illustrated in these patents, and of which these patents are illustrative, is so constructed that its side walls or portions thereof may be swung or moved into various positions so as to give either a tight body or bed for carrying small material such as grain and the like, or a relatively wide flat body or bed for carrying such material as corn on the ear, hay, and other relatively large bodies.

The main object of the present invention is to provide an improved construction of bracket or the like for holding the side walls or movable portions thereof in the different adjusted positions into which they may be set from time to time. In this connection, one of the objects is to so construct the said brackets that they will operate with a minimum amount of friction or resistance when moving the side walls from one position to another; to provide a maximum amount of strength combined with a minimum size and weight of bracket; and to provide a very simple construction and arrangement for locking the bracket into the different adjusted positions.

Other objects and uses of the invention will appear from a detailed description of the same which consists in the features of construction and combinations of parts hereinafter described and claimed.

In the drawing:

Figure 1 shows a cross section through a wagon body or bed provided with brackets embodying the features of the present invention;

Fig. 2 shows a detailed face view of the bracket on enlarged scale;

Fig. 3 shows a detailed fragmentary side view of the bracket in locked position and on an enlarged scale;

Fig. 4 shows a view similar to Fig. 3 with the lever moved into unlocking position; and

Fig. 5 shows a cross section taken on the line 5-5 of Fig. 2, looking in the direction of the arrows.

The wagon bed or body illustrated in the drawing includes the bottom or floor 6, the sides 7 and 8, and suitable end walls, the front end 9 appearing in Fig. 1. The side walls 7 and 8 are provided with hinged or pivoted sections 10 and 11, and these sections may comprise the entire side walls or portions thereof. In the construction illustrated these hinged or pivoted portions constitute only the upper portions of the side walls, the lower portions 12 and 13 being rigid or stationary. The sections 10 and 11 are hinged to the stationary sections 12 and 13 by the hinges 14, so that they can be turned down into the dotted line position illustrated in Fig. 1.

Suitable brackets designated in their entirety by the numeral 15 are provided for securing the hinged sections either in their fully raised or fully lowered or partially lowered position.

Certain of the constructions thus far described have been previously known and used, as, for example, in the above mentioned Letters Patent of the United States. The bracket which I shall now describe more in detail embodies certain features of invention not heretofore known or used.

Each of the brackets 15 includes the upper and lower sections 16 and 17 respectively, the upper end of each upper section being pivoted or hinged to the movable side wall section or a bracket connected thereto at the point 18, and each of the lower sections 17 is pivoted or hinged to the wagon bed or body or a bracket thereon at the point 19. The two sections 16 and 17 of each bracket are slidably or movable with respect to each other and means are provided for locking them against such movement at one

or more desired points depending upon the position at which it is intended to secure the hinged side wall of the wagon. Each of the sections 16 and 17 comprises a channel bar, 5 and these channel bars are placed back to back, a fact which will be clearly understood from an examination of Fig. 5 in particular. In the said figure the back portions 20 and 21 of the two channels are seen to lie in flat 10 contact or engagement; on the other hand the flanges 22 and 23 of the section 16 and the flanges 24 and 25 of the section 17 face respectively in opposite directions.

Clips 26 and 27 are secured respectively 15 to the end portions of the sections 16 and 17. By this arrangement the clip on the section 16 slides with respect to the section 17, and the clip on the section 17 slides with respect to the section 16. These clips are for 20 the purpose of retaining the two sections at all times in co-operative relationship.

A locking lever 28 is pivoted on the clip 26 by means of the pin 29. This pivoting is secured by bending or folding the end 25 portion of the lever around the pin so as to completely embrace the same. The central part 30 of the portion so bent or folded completely encircles the pin and lies between the flanges 24 and 25 of the lower section 17, 30 whereas the sides of said end portion are mutilated as at 31 and 32, the mutilations registering or corresponding in position to the flanges 24 and 25.

When the lever is turned up in the position shown in Fig. 4, the mutilated portions 35 31 and 32 will permit the clip 26 and lever to move or slide with respect to the bracket section 17, whereas when the lever is turned down into the position in Fig. 3, the mutilated sections will be turned around so as 40 to no longer register with the flanges 24 and 25. The lever can only be turned into the position of Fig. 3 when the clip 26 stands in such a position that the lever will register with suitable notches or recesses 45 33 formed in the edge portions of the flanges 24 and 25. When the parts are so registered the lever may be turned down into the position of Fig. 3, and thereupon the two sections 50 of the bracket will be locked against any sliding movement with respect to each other. Manifestly the notches may be formed at any suitable positions throughout the length of the flanges 24 and 25, but generally they 55 will be formed at a position where the side of the wagon will be locked in fully raised position, at a point where the side will be locked in fully lowered position, and at some intermediate point.

I desire to particularly call attention to 60 the fact that the placing of the channel sections back to back serves to give a very large surface of contact between said sections, thereby reducing the sliding friction and also increasing the strength and permanency of the structure; besides which this arrangement exposes the edge or flanged portions of the section 17 and so as to simplify the provision of the locking notches or recesses. 70

I claim:

1. In a wagon bed or body, the combination of a stationary bed portion and a side portion hinged or pivoted thereto, and a bracket connecting the hinged or pivoted 75 portions to the stationary portion, said bracket comprising in combination a pair of channel bars placed back to back with their adjacent end portions overlapping each other, and with their other end portions connected respectively to the stationary and the hinged or pivoted portions of the wagon, and means for locking the two channel sections against relative sliding movement comprising a lever pivoted to the 80 end portion of one channel and having its sides overlying the flanges of the other channel, said sides being segmentally mutilated, and there being suitable recesses in the flanges of the channel, whereby when the 85 lever registers with the said recesses it may be fully turned to engage its side portions with the recesses in locking fashion, and whereby when the lever is turned into another position, its mutilated portions 90 register with the recesses and permit sliding movement between the parts, substantially as described.

2. An adjustable bracket comprising in combination a pair of channel sections 100 placed back to back and with their end portions overlapping each other, and means for locking said channel sections against relative sliding movement comprising a lever pivoted to one section and having its sides 105 overlying the flanges of the other section, said sides being segmentally mutilated, and the flanges so overlaid being suitably notched, whereby when the sections are in proper relative position the side portions of 110 the lever engage such notches or recesses in locking fashion, and whereby when the lever is turned into another position, the mutilated portions register with the notches to 115 permit relative sliding movement between the sections, substantially as described.

ALEXANDER F. KUHNEN.
